UNITED STATES PATENT OFFICE.

JOHN H. EARLEY, OF PHILADELPHIA, PENNSYLVANIA.

METALLIC PALLET.

No. 822,194.

Specification of Letters Patent.

Patented May 29, 1906.

Application filed October 8, 1904. Serial No. 227,684.

To all whom it may concern:

Be it known that I, JOHN H. EARLEY, of Philadelphia, in the State of Pennsylvania, have invented certain new and useful Improvements in Metallic Pallets, whereof the following is a specification, reference being had to the accompanying drawings.

My invention relates to devices particularly adapted for supporting bricks in a dry-ing-kiln in removable relation therewith.

My invention provides such a pallet which is more durable than the ordinary wooden pallets heretofore employed, which may be so formed of pressed sheet metal as to have integral bracing-flanges along its opposite longitudinal edges arranged to admit a protective coating throughout their extent, and which is particularly advantageous in that it comprises runners arranged to slide freely on supporting-tracks and prevent said bracing-flanges from catching thereon.

As hereinafter described, my invention comprises a plane panel of sheet metal of greater length than width, having cylindri-

25 form bracing-flanges along its longitudinal edges and bracing runner-bars secured transversely at its ends, which latter are thus arranged to be supported by iron flanges or tracks arranged in tiers on a truck or car, so 30 that the pallets may be slid thereon one after another.

My invention comprises the various novel features of construction and arrangement hereinafter more definitely specified.

35 In the drawings, Figure I is a plan view of a pallet conveniently embodying my improvements. Fig. II is an inverted plan view of said pallet. Fig. III is an end view of said pallet.

40 In said figures, 1 is a plane panel, of pressed sheet metal, having its opposite longitudinal edges curled beneath it to form integral cylindriform tubular bracing-flanges 2, as best shown in Fig. III.

45 Referring to Fig. III, it is to be noted that there are spaces 12 between the inner edges of the flanges 2 and the adjacent under surface of the panel 1 and that such construction is desirable to permit the entire surface 50 of said panel and flanges to be provided with a protective coating of paint or other suitable material, said panels and the end bars or runners 4 being preferably formed of pressed steel, which would be corroded by the moisture from the bricks thereon unless provided with a protective coating. Said panel 1 is

provided at its opposite ends with bracing bars or runners 4, whose central portions 5 are in contact with the under side of the panel 1 and secured thereto by the rivets 6. 60 As best shown in Fig. III, the free ends 8 of said runners 4 are curved upwardly to embrace the flanges 2 and serve as fenders for said flanges, and thus facilitate the introduction of the pallet upon the flange 10 or 65 tracks indicated by the dotted lines in Fig. III, which may be on a truck and support a plurality of the pallets, which are slid thereon one after another. It may be noted that the construction is such as to permit the pallet 70 to slide freely without striking the flanges 2 on said tracks 10 when introduced at an angle oblique thereto, as well as when in parallel position thereon, as shown in Fig. III.

It is to be understood that I do not desire 75 to limit myself to the precise details of construction and arrangement herein set forth, as various modifications may be made therein without departing from the essential features of my invention.

I claim—

1. A metallic pallet comprising a plane sheet-metal panel provided with bracing-flanges at its opposite longitudinal edges, and runner-bars at its ends; said bars having central portions in contact with said panel and having their free ends bent to overlap said flanges exterior thereto, substantially as set forth.

2. A metallic pallet provided with integral 90 cylindriform curved bracing-flanges at its opposite longitudinal edges, and primarily separate runner-bars secured at its opposite ends beneath said panel; the free ends of said bars being arranged to engage said longitudinal 95 flanges; and, rivets securing said runner-bars to said panels, substantially as set forth.

3. A metallic pallet comprising a plane sheet-metal panel having its opposite longitudinal edges curled beneath it in integral 100 cylindriform bracing-flanges, the edges of said flanges being apart from the under surface of said panel; runner-bars at the ends of said panel upon the same side as said cylindriform flanges; said bars having central portions in contact with said panel and having their ends bent to overlap said flanges; and, rivets extending through said panel and said bars, substantially as set forth.

4. A metallic pallet comprising a plane 110 sheet-metal panel provided with bracing-flanges at its opposite longitudinal edges;

and, runner-bars at its ends; the free ends of said bars extending away from said panel and forming supports respectively local to the opposite longitudinal edges of said panel, substantially as set forth.

5. A metallic pallet comprising a plane sheet-metal panel provided with bracing-flanges at its opposite longitudinal edges, and, runner-bars at its ends; the free ends of 10 said bars extending away from said panel and

forming upwardly-curved supports respectively local to the opposite longitudinal edges of said panel, substantially as set forth.

In testimony whereof I have hereunto signed my name, at Philadelphia, Pennsylvania, this 6th day of October, 1904.

JOHN H. EARLEY.
